ELEVATOR INDUCTOR SWITCH

Conwell Savage, New York, N. Y., assignor to
Westinghouse Electric Corporation, East Pitts-
burgh, Pa., a corporation of Pennsylvania

Application May 20, 1950, Serial No. 163,291

9 Claims. (Cl. 200—87)

1

This invention relates to electromagnetic de-
vices, and it has particular relation to inductor
switches suitable for use in controlling the oper-
ation of electrical elevators.

Inductor switches or relays have been em-
ployed widely in the control of electrical eleva-
tors. As an example of an elevator control sys-
tem employing inductor switches, reference may
be made to the Mattingly Patent 1,884,514.

For efficient operation of an elevator system,
an inductor switch should initiate a slowdown or
stopping operation at a predetermined distance
from a floor at which an elevator car is to stop.
The accuracy of the inductor switch should not
be affected by lateral movements of an elevator
car in its hoistway. Similar comments apply to
inductor switches employed for releveling an
elevator car at a floor. In the Harry Berkovitz
patent application, Serial No. 129,665, filed No-
vember 26, 1949, and assigned to the same as-
signee, an improved relay structure is provided.
Berkovitz employs magnetic channels as induct-
or plates. Each channel extends in a direction
parallel to the path of travel of the elevator car.
The Berkovitz inductor switch employs a coil
mounted with its axis transverse to the direction
of travel of the elevator car. This coil has a
magnetic structure which includes a pair of
spaced polar magnetic plates which define a non-
magnetic gap therebetween. When the coil is
energized, the polar plates are excited with op-
posite magnetic polarities to produce a magnetic
field in the non-magnetic gap. Each polar plate
may have a slot within which a magnetic ar-
mature is positioned for movement toward and from
the non-magnetic gap. Each magnetic armature
thus is effectively shielded by its associated polar
plate.

During the travel of the elevator car in its
hoistway, a channel enters the non-magnetic gap
and has each of its flanges adjacent a separate
one of the polar plates. The magnetic reluctance
between the polar plates thus is substantially re-
duced, and sufficient magnetic flux flows to actu-
ate the magnetic armatures. Preferably, the
polar plates are offset from the axis of the coil
to permit the inductor switches to be stacked
in the direction of travel of the elevator car for
successive operation within a short distance by a
common channel.

In accordance with the invention, an induct-
or switch of the general type disclosed in the
aforesaid Berkovitz application is provided with
an improved armature and polar plate construc-
tion. This improved construction reduces the
magnetic forces acting between the polar plates
and the armatures with a resultant increase in
efficiency of operation. Shielding also is im-
proved.

In addition the invention provides enclosures

2

for the armatures and the contact assemblies op-
erated by the armatures. The enclosures protect
the armatures, air gaps and contact assemblies
with no impairment in operation thereof.

5 The invention also comprises improved links
associated with the armatures for operating the
associated contact assemblies. Connections be-
tween the links and the associated components
are effected by simple key and keyhole connec-
tions which facilitate construction and servicing
of the equipment and which assure negligible
friction for the moving parts.

10 It is, therefore, an object of the invention to
provide an improved, simple and sturdy inductor
switch which has negligible friction between
moving parts.

15 It is a second object of the invention to pro-
vide an inductor switch having an armature mov-
ably associated with a polar plate and having an
air gap between the armature and the polar plate
which minimizes magnetic forces therebetween.

20 It is a third object of the invention to provide
an inductor switch having an improved protec-
tive enclosure.

25 Other objects of the invention will be apparent
from the following description taken in conjunc-
tion with the accompanying drawing, in which:

Figure 1 is a top plan view with parts in
section of an inductor switch embodying the
invention;

Fig. 2 is a view in side elevation with parts
broken away of the inductor switch shown in
Fig. 1;

Fig. 3 is a view in side elevation of a first
link employed in the inductor switch of Fig. 1;

Fig. 4 is a view in side elevation of a second
link employed in the inductor switch of Fig. 1;
and

Fig. 5 is a detail view in plan of a portion
40 of an arm employed in the inductor switch of
Fig. 1.

Referring to the drawing, Fig. 1 shows an in-
ductor switch 1 associated with an inductor plate
P. The inductor plate P is in the form of a chan-
nel having flanges P1 and P2.

45 When employed for controlling an elevator
system, one of the inductor plates P would be
positioned in the hoistway of an elevator car for
each of the floors served by the elevator car. The
50 inductor switch 1 would be secured to the elevator
car for movement therewith. As shown in Fig. 2,
the inductor switch 1 would move with the ele-
vator car in the direction of the arrows 3 along a
path parallel to the inductor plate P.

55 The inductor switch 1 includes a base structure
5 which is constructed of non-magnetic material.
This base structure supports a magnetic structure
7 which defines a large non-magnetic air gap for
reception of the inductor plate P.

The magnetic structure 7 includes a magnetic

core 9 which is located within a coil 11. Polar assemblies 12 and 13 are secured to the respective ends of the core 9.

The polar assembly 13 comprises a plate 17 which has a slot 19 therein. A magnetic armature 21 is located in the slot for movement about an axis towards and from the air gap within which the inductor plate P is received.

The magnetic armature 21 may be pivotally mounted with respect to the plate 17 in any suitable manner. In a preferred embodiment, a flexible leaf spring 23 has its ends secured in any suitable manner as by rivets respectively to the magnetic armature 21 and the plate 17. The spring provides an effective hinging action which is relatively free of friction.

The magnetic plate 17, the magnetic core 9 and the magnetic armature 21 may be constructed of a soft magnetic material such as soft iron or steel. The spring 23 may be constructed of non-magnetic or magnetic material. A bronze spring ribbon has been found to be satisfactory for the spring 23.

Movement of the magnetic armature 21 is intended to operate a switch or contact assembly 25. The switch assembly includes an electroconductive leaf spring 27 which has a contact button 29 adjacent one end thereof. This contact button cooperates with a contact button 31 secured to one end of an electroconductive strip 33. The spring 27 and the strip 33 are secured to the base structure 5 but are insulated from each other in any suitable manner. For example, insulating spacers 35 may be employed for insulating the spring and strip from each other and from the base structure.

In order to operate the switch assembly, an arm 37 is secured to the magnetic armature 21. This arm has a lip 39 which is substantially parallel to but spaced from the spring 27. A link 41 is employed for connecting the lip 39 to the spring 27 which serves as an operating member for the switch assembly.

As shown more clearly in Fig. 4, the link 41 is formed of a sheet of insulating material, such as a phenolic resin, and has a double keyhole slot formed therein. This double keyhole slot includes a large opening 41a which forms a common part of the two keyhole slots. The large opening 41a communicates with two oppositely directed small openings 41b and 41c.

By comparing Figs. 4 and 5 it will be noted that the lip 39 has a key formation. The key is defined by two notches 39a and 39b which provide a head 39c proportioned to pass through the opening 41a, but too large to pass through the small openings 41b and 41c. In addition the notches define a neck 39d which is proportioned for reception in one of the small openings 41b or 41c. Consequently the lip 39 may be introduced through the opening 41a of the link 41 and then moved at right angles relative to the link for the purpose of moving the neck 39d into one of the small openings 41b or 41c.

In a similar manner, the left-hand end of the spring 27 (as viewed in Fig. 1) is constructed as a key having a head 27c and a neck 27d proportioned for reception in one of the small openings of the associated link 41.

The bias exerted by the spring 27 is in a direction tending to move the spring away from the lip 39. The bias exerted by the spring 23 on the armature 21 and the lip 39 is in a direction tending to move the lip away from the spring 27. This tends to hold the lip and the spring 27 in

the small openings of the associated link 41. At the same time, the link has sufficient play to provide a hinge action between the link and the lip 39 and between the link and the spring 27. For this reason forces are transmitted between the magnetic armature 21 and the spring 27 with negligible friction. It will be noted that the bias exerted by the spring 27 urges the buttons 29 and 31 into engagement with each other.

In order to protect the magnetic armature 21 and the associated switch assembly, a non-magnetic sheet may be secured over the slot 19 in any suitable manner. For example the sheet 43 may be constructed from sheet brass and may be brazed to the plate 17.

In addition a cover 45 is provided. Conveniently this cover may be constructed of non-magnetic material. The cover is proportioned to engage the base structure 5 and the plate 13 to complete an enclosure for the magnetic armature 21 and the associated switch assembly. The cover may be detachably secured to the base structure and the plate 17 in any suitable manner as by machine screws 47.

By inspection of Fig. 1, it will be observed that the sheet 43 serves as a stop limiting travel of the magnetic armature in one direction. Travel of the armature in the opposite direction may be limited by means of a rib 49 which is an integral part of the structure of the cover 45.

It will be understood that suitable conductors 51 and 53 are provided for connecting the spring 27 and the strip 33 to an external circuit.

The polar assembly 15 includes a plate 55 having a slot 57 within which a magnetic armature 59 is positioned for pivotal movement relative to the plate 55. A non-magnetic sheet 61 is employed for covering the slot 57. A cover 63 is provided to complete an enclosure for the magnetic armature. The plate 55, the magnetic armature 59, the sheet 61 and the cover 63 are similar respectively to the plate 17, the magnetic armature 21, the sheet 43 and the cover 45 which are described above, but it will be noted that the polar assembly 15 is reversed relative to the polar assembly 13 about an axis transverse to the axis of the coil. The magnetic armature 59 is pivotally associated with the plate 55 in the same manner by which the magnetic armature 21 is associated with the plate 17.

An electrical switch or contact assembly 65 is associated with the magnetic armature 59. This switch assembly may be similar in construction and operation to the switch assembly 25. However, in the specific embodiment of Fig. 1, the switch assembly 65 is of the make or contact-closing type as contrasted with the break or contact-opening type represented by the switch assembly 25.

The switch assembly 65 includes a leaf spring 67 having a contact button 69 at one end. This spring and the button may be exactly similar to the spring 27 and the button 29 previously discussed.

The spring 67 and the button 69 cooperate with an electroconductive strip 71 and a contact button 73. The strip 71 and the spring 67 are insulated from each other and are secured to the base structure 5 in the same manner by which the spring 27 and strip 33 are secured to the base structure.

The magnetic armature 59 has associated therewith an arm 75 having a lip 77 which corresponds to the arm 37 and the lip 39 previously described. A link 79 is employed for trans-

mitting forces between the spring 67 and the lip 71.

As shown in Fig. 3, the link 79 has two small openings 79b and 79c which correspond to the openings 41b and 41c of Fig. 4. However, the link 79 has a large opening 79a which is much longer than the opening 41a of Fig. 4 and has a bridge 79d which divides the opening 79a into two portions.

The spring 67 and the lip 71 are associated with the link 79 in the same manner by which the spring 21 and the lip 39 are associated with the link 41. However, by inspection of Fig. 1 it will be observed that the strip 71 extends through the opening 79a above the bridge 79d. Consequently when the link 79 moves in an upward direction, as viewed in Fig. 1, the bridge 79d engages the strip 71 to serve as a stop limiting further motion of the link relative to the strip.

The bias exerted by the spring 67 is in a direction urging the button 69 away from the button 73. The bias exerted on the armature 59 by the associated hinging spring is in a direction urging the lip 71 away from the spring 67.

It is believed that the operation of the inductor switch now may be set forth. As long as the coil 11 is deenergized, no magnetic flux is supplied to the magnetic structure, and the switch assemblies remain in the positions illustrated. Movement of the inductor plate P between the polar assemblies 13 and 15 consequently has no effect on the inductor switch.

When the coil 11 is energized, a magnetomotive force is established between the polar assemblies 13 and 15. If the inductor plate P is displaced from the inductor switch, a substantial air gap exists between the magnetic armatures 59 and 21 and the magnetic forces acting thereon are extremely small. Consequently the energization of the coil 11 has no effect on the switch assemblies as long as the inductor plate P is displaced from the inductor switch.

When the inductor plate P enters the gap between the armatures, the magnetic reluctance offered to the flow of magnetic flux produced by current flowing in the coil 11 is materially reduced and substantial forces act on the magnetic armatures urging them towards the inductor plate.

The magnetic armature 21 is urged from the position illustrated in full lines in Fig. 1 towards the position illustrated by the dotted line. In moving, the magnetic armature 21 operates through the link 41 to separate the buttons 29 and 31. This interrupts any circuit which is completed through the buttons 29 and 31.

At the same time the magnetic armature 59 moves towards the flange P1. Such movement operates through the link 79 to move the button 69 into engagement with the button 73. The engagement of the buttons 69 and 73 may be employed for completing any electrical circuit connected to the spring 67 and the strip 71.

Inasmuch as each of the magnetic armatures moves with respect to its associated plate, such movement may change the magnetic forces acting therebetween. To minimize such changes in magnetic forces, the air gap between each magnetic armature and its associated magnetic plate is larger at a substantial distance from the spring 23 than for a lesser distance from the spring 21. For example, as shown in Fig. 2, the slot 19 may have a substantially trapezoidal configuration which is defined by walls 17a, 17b, 17c and 17d. The magnetic armature 21, as shown in Fig. 2, has a rectangular outline. By inspection of Fig.

2, it will be noted that the spacing or air gap between the magnetic armature and the left-hand wall 17a is comparatively large. The walls 17b and 17d also are substantially spaced from the left-hand end of the magnetic armature as viewed in Fig. 2 and gradually approach the magnetic armature at points closer to the spring 23.

The effect of this construction of the slot is such that most of the magnetic flux passing between the magnetic armature and the associated plate 17 crosses the air gap therebetween at points which are comparatively close to the spring 23. The forces produced by such magnetic flux for the most part have small torque arms acting about the hinge established by the spring 23. For this reason the torque which results from movement of the magnetic armature 21 relative to the plate 17 is minimized.

Furthermore, by inspection of Fig. 1, it will be observed that the right-hand end of the magnetic armature 21 does not move appreciably with respect to the associated plates 17. This is for the reason that the right-hand end of the magnetic armature is adjacent the hinge axis established by the spring 23. Since most of the flux passing between the magnetic armature and the plate 17 flows through an air gap which does not change appreciably in position, it follows that the change in the magnetic forces resulting from such small variations in the air gap are also comparatively small.

It will be noted that the magnetic plate 17 completely surrounds the magnetic armature in a plane parallel to the direction of movement of the inductor switch relative to the inductor plate P. For this reason the inductor switch detects accurately the approach of the inductor plate from either direction.

Although the invention has been described with reference to certain specific embodiments thereof, numerous modifications falling within the spirit and scope of the invention are possible.

I claim as my invention:

1. In an electromagnetic device, an electrically-energizable coil, a magnetic structure establishing a path having a non-magnetic gap for magnetic flux produced by current flowing in the coil, said magnetic structure comprising a magnetic core disposed in the coil, a magnetic polar structure adjacent an end of the magnetic core, said polar structure having a slot extending therethrough, a magnetic armature disposed in said slot for movement relative to the polar structure about an axis towards and from the non-magnetic gap, the polar structure and the magnetic armature being disposed on one side of the non-magnetic gap, said magnetic structure having an air gap between the polar structure and the magnetic armature which is larger at a distance from said axis than at a position closer to said axis.

2. A device as claimed in claim 1 wherein the magnetic armature is of substantially rectangular configuration and said slot is of tapered construction with the small end of the slot closer than the large end of the slot to said axis.

3. A device as claimed in claim 1 wherein the magnetic polar structure substantially completely surrounds the periphery of the magnetic armature.

4. In an electromagnetic device, an electrically-energizable coil, a magnetic structure establishing a path having a non-magnetic gap for magnetic flux produced by current flowing in the coil, said magnetic structure comprising a magnetic core disposed in the coil, a magnetic polar struc-

ture adjacent an end of the magnetic core, said polar structure having a slot extending therethrough, a magnetic armature disposed in said slot for movement relative to the polar structure about an axis towards and from the non-magnetic gap, the polar structure and the magnetic armature being disposed on one side of the non-magnetic gap, said magnetic polar structure extending in a plane parallel to said axis around four sides of the magnetic armature to provide effective magnetic shielding in said plane for the magnetic armature.

5. In an electromagnetic device, an electrically-energizable coil, a magnetic structure establishing a path having a non-magnetic gap for magnetic flux produced by current flowing in the coil, said magnetic structure comprising a magnetic core disposed in the coil, a magnetic polar structure adjacent an end of the magnetic core, said polar structure having a slot extending therethrough, a magnetic armature disposed in said slot for movement relative to the polar structure about an axis towards and from the non-magnetic gap, the polar structure and the magnetic armature being disposed on one side of the non-magnetic gap, contact structure comprising contacts operated by said armature, and enclosing structure providing a substantially sealed enclosure for the armature and the contact structure, said enclosing structure including a first non-magnetic cover for said slot, said cover being interposed between the magnetic armature and said non-magnetic gap, and a second cover detachably secured to the polar structure, said polar structure constituting a part of the enclosing structure.

6. In a magnetically-operated device, a source of magnetomotive force, a magnetic structure defining a magnetic path having a non-magnetic gap for magnetic flux produced by said source, said magnetic structure including a magnetic polar plate having a surface abutting said gap, the polar plate having an aperture communicating with the gap, a magnetic armature disposed substantially in said aperture in spaced relationship relative to the walls of the aperture, means mounting the magnetic armature for movement relative to the polar plate about an axis towards and from the gap, the gap between the polar plate and the armature being greater at points a substantial distance from the axis than at points closer to the axis, and translating means responsive to movement of the armature relative to the polar plate.

7. In a magnetically-operated device, a source of magnetomotive force, a magnetic structure defining a magnetic path having a non-magnetic gap for magnetic flux produced by said source, said magnetic structure including a magnetic polar plate having a surface abutting said gap, the polar plate having an aperture communicating with the gap, a magnetic armature disposed substantially in said aperture in spaced relationship relative to the walls of the aperture, means mounting the magnetic armature for movement relative to the polar plate about an axis towards and from the gap, the gap between the polar plate and the armature being greater at points a substantial distance from the axis than at points closer to the axis, and translating means responsive to movement of the armature relative to the polar plate, said mounting means comprising a resilient ribbon disposed in a plane trans-

verse to said axis, the ends of the ribbon being secured to the polar plate and to the armature respectively adjacent to said axis.

8. In a magnetically-operated device, a source of magnetomotive force, a magnetic structure defining a magnetic path having a non-magnetic gap for magnetic flux produced by said source, said magnetic structure including a magnetic polar plate having a surface abutting said gap, the polar plate having an aperture communicating with the gap, a magnetic armature disposed substantially in said aperture in spaced relationship relative to the walls of the aperture, means mounting the magnetic armature for movement relative to the polar plate about an axis towards and from the gap, said gap being unobstructed in a predetermined direction, whereby a magnetic body may be passed through the gap in said direction, said polar plate substantially completely surrounding the magnetic armature in a plane parallel to said direction, and translating means responsive to movement of the armature relative to the polar plate.

9. In a magnetically-operated device, a source of magnetomotive force, a magnetic structure defining a magnetic path having a non-magnetic gap for magnetic flux produced by said source, said magnetic structure including a magnetic polar plate having a surface abutting said gap, the polar plate having an aperture communicating with the gap, a magnetic armature disposed substantially in said aperture in spaced relationship relative to the walls of the aperture, means mounting the magnetic armature for movement relative to the polar plate about an axis towards and from the gap, said gap being unobstructed in a predetermined direction, whereby a magnetic body may be passed through the gap in said direction, said polar plate substantially completely surrounding the magnetic armature in a plane parallel to said direction, a non-magnetic member interposed between the magnetic armature and the gap, said member being secured to the polar plate to cover said aperture, and a cover secured to the polar plate to provide a substantially complete enclosure for the translating means, said enclosure being defined in part by the cover, the member and the polar plate, and translating means responsive to movement of the armature relative to the polar plate.
